United States Patent Office

Des. 181,251
Patented Oct. 22, 1957

181,251

SLIP OR SIMILAR ARTICLE

John T. Grady, Hawthorne, N. J.

Application April 4, 1957, Serial No. 45,586

Term of patent 3½ years

(Cl. D3—26)

Fig. 1.

Fig. 2.

I claim:

The ornamental design for a slip or similar article, substantially as shown.
